UNITED STATES PATENT OFFICE.

THOMAS CLARENCE HEISEY, OF NEWARK, OHIO, ASSIGNOR TO A. H. HEISEY & COMPANY, OF NEWARK, OHIO, A COMMON LAW COMPANY.

DESIGN FOR A TUMBLER.

Application filed February 13, 1926. Serial No. 16,511. Term of patent 14 years.

To all whom it may concern:

Be it known that I, THOMAS CLARENCE HEISEY, a citizen of the United States, residing at Newark, in the county of Licking, State of Ohio, have invented a new, original, and ornamental Design for a Tumbler, of which the following is a specification, reference being had to the accompanying drawing, forming a part thereof.

The figure is a perspective view of a tumbler showing my new design.

I claim:

The ornamental design for a tumbler, as shown.

THOMAS CLARENCE HEISEY.
